UNITED STATES PATENT OFFICE.

ELDRIDGE R. JOHNSON, OF MERION, PENNSYLVANIA, ASSIGNOR TO VICTOR TALKING MACHINE COMPANY, A CORPORATION OF NEW JERSEY.

TALKING-MACHINE.

1,379,345.

Specification of Letters Patent. Patented May 24, 1921.

Application filed October 2, 1914, Serial No. 864,564. Renewed October 9, 1919. Serial No. 329,646.

To all whom it may concern:

Be it known that I, ELDRIDGE R. JOHNSON, a citizen of the United States, and a resident of Merion, county of Montgomery, 5 State of Pennsylvania, have invented certain new and useful Improvements in Talking-Machines, of which the following is a specification.

One object of this invention is to provide 10 an improved collapsible talking machine, and more specifically an improved collapsible talking machine including a cabinet and sound reproducing means inclosed therein in which the sound reproducing means includes a rotary record support which is arranged to be moved from an inoperative position, in which it is entirely inclosed by the cabinet, to an operative position, in which it projects outwardly from and is 20 only partly inclosed by the cabinet.

Another object of this invention is to provide an improved talking machine including a cabinet and sound reproducing means inclosed thereby and in which the sound reproducing means includes a record support movable from an inoperative position to an operative position as the result of the movement of a closure forming a part of the cabinet.

30 Other objects of this invention are to provide in a talking machine improved sound amplifying means; to provide an improved arrangement for a disk record support; and to provide other improvements as will appear hereinafter.

In the accompanying drawings, Figure 1 is a fragmentary front elevation of a talking machine constructed in accordance with this invention, the parts thereof being shown 40 as when in operation; Fig. 2 a vertical central section of the same; Fig. 3 a vertical central section of the same showing the parts as in inoperative condition; and Figs. 4 and 5 are perspective views of parts of the same.

The embodiment of this invention shown in the drawings comprises an upright rectangular cabinet 1 including vertical parallel side walls 2 and 3, a vertical back wall 4, 50 a horizontal top wall 5 and a horizontal bottom wall 6. The interior of the cabinet is sub-divided by two vertical partitions 10 and 11 which extend from the top wall 5 to the bottom wall 6 and from the back wall 4

forwardly to the plane of the front of the 55 cabinet, and between each of these vertical partitions 10 and 11 and the corresponding side walls 2 and 3 are horizontal partitions 12 forming record compartments which are provided with suitable doors 13.

60 To provide suitable compartments for sound reproducing means and sound amplifying means, a horizontal partition 15 is arranged approximately midway between the top wall 5 and the bottom wall 6 and extends from one of the vertical partitions 10 to the other vertical partition 11. The space within the cabinet above this horizontal partition 15 and between the two vertical partitions 10 and 11, is divided by a wooden 65 partition 20 which extends from one of the vertical partitions 10 to the other vertical partition 11, thus providing a lower compartment 21 adapted to contain sound reproducing mechanism and an upper compartment 22 adapted to contain sound amplifying means. The rear portion of the wooden partition 20 dividing these two compartments is preferably substantially horizontal and extends inwardly from the back 70 wall 4 of the cabinet to a horizontal line perpendicular to the side walls 10 and 11 and approximately midway between the back wall 4 and the front of the cabinet. The front portion of this partition 20 is 75 preferably inclined obliquely upwardly from the horizontal portion to the front plane of the cabinet and in a plane perpendicular to the vertical partitions 10 and 11.

Extending between the two vertical partitions 10 and 11, and secured thereto, flush with the outer edges thereof, are two vertically spaced horizontal strips or cleats 25 and 26, the inner surfaces of which are preferably in abutment, respectively, with the front edges of the horizontal partition 15, forming the bottom wall of the lower compartment 21, and the partition 20 which divides the lower compartment 21 from the upper compartment 22. The open space 27 90 between the upper cleat 26 and the top wall 5 and between the vertical partitions 10 and 11 serves as a sound outlet from the sound amplifying compartment 22, and is preferably controlled by two vertical doors 30 95 and 31 which are hinged respectively to the vertical partitions 10 and 11. The space below the horizontal partition 15 is sub- 100 105

divided by a horizontal partition 35 to form suitable compartments 36 and 37, one of which may be provided with doors 38 and the other with a drawer 39, for the storage 5 of records or accessories.

For supporting a sound record support and a motor for actuating the same a substantially flat rigid inclined carriage 40 extends from the vertical partition 10 to the 10 vertical partition 11 in a plane perpendicular to these partitions. This carriage is inclined from its front edge rearwardly and upwardly and is mounted to slide in its own plane upon two parallel inclined cleats 41 which are rigidly secured against the inner 15 sides of the vertical partitions 10 and 11, and within the sound reproducing compartment 21. The path of the carriage is so arranged that the carriage may be reciprocated between an inoperative position where it is entirely inclosed by the cabinet (as shown in dotted lines in Fig. 3), and an operative position, where its front portion projects outwardly from the cabinet (as shown 20 in Figs. 1 and 2).

Secured to and depending from the carriage 40 is a motor 45 which may be of any suitable construction, but which is shown as a spring motor provided with a winding gear 46, arranged to be rotated by a crank 47 which projects fully through an inclined slot provided therefor in the vertical partition 11. A spindle 48 projects perpendicularly through the carriage 40 in an approximately central aperture provided therefor in the carriage. This spindle is arranged to be rotated by the motor 45 about an axis fixed with respect to the carriage 40 and coincident with the longitudinal axis of the 35 spindle. Carried by the upper end of this spindle 48 is a turntable or rotary record support 50, which is arranged normally in a plane parallel to the carriage 40 to support a disk sound record 51.

45 For counterbalancing the carriage 40 and parts carried thereby, a vertically elongated counterweight 55 is arranged to reciprocate vertically in a compartment 56 formed between the back wall 4 of the cabinet and a 50 vertical partition 57 which extends from the horizontal partition 15 to the horizontal partition 35. This counterweight is secured at its upper end to one end of a flexible connector 58 which passes from the counterweight upwardly over a pulley 59 rotatively secured to the inner surface of the back wall 4 and is connected at its other end to the motor 45, the arrangement being such that the flexible connector acts upon the motor 45 55 and its carriage 40 in an inclined direction parallel to the line of movement of the carriage. The counterbalance 55 is preferably of a sufficient weight to overbalance the tendency of the carriage 40 to slide downwardly on its ways 41 under the action of

the weight of the carriage and the weights of the parts carried thereby, and to tend to slide the carriage upwardly.

For inclosing the front of the sound reproducing compartment 21 and for automatically reciprocating the carriage 40 there is provided a flat substantially rigid door or closure 70 which when closed is arranged vertically and entirely fills the space between the horizontal strips 25 and 26 and the vertical partitions 10 and 11. For supporting the door 70 to oscillate about a fixed horizontal axis from a vertical position to a horizontal position in which the outer surface of the door rests upon the upper surface 75 of the lower cleat or strip 25, and in which the door projects partially into the cabinet, two oppositely disposed brackets 71 are rigidly secured to the inner surface of the door adjacent the lower edge thereof. These 80 brackets are provided respectively with two horizontally aligned cylindrical apertures 72 in which engage two coaxial pivots 73 which project respectively through the vertical partitions 10 and 11 and which are rigidly 85 secured thereto by plates 74 integral with the pivots respectively. The door or closure 70 is operatively connected to the carriage 40 by two oppositely disposed parallel links 75 which extend inwardly from the 90 door. The outer end of each of these links is pivotally connected to a bracket 76 rigidly secured to the inner surface of the door 70, and the inner end of each of these links is 95 pivotally secured to a bracket 77 rigidly secured to the upper surface of the front portion of the carriage 40. The arrangement is such that when the door 70 is in a horizontal position, the links 75 will lie flat 100 against the upper surface of the carriage, and the weight of the door 70 acting through the links will hold the carriage 40 in an operative position (as shown in Figs. 1 and 2) 105 against the action of the counterweight 55. When the door 70 is swung from a horizontal position into a closed vertical position, the links 75 will act to slide the carriage 40 inwardly along the tracks 41 and into an inoperative position as shown in 110 dotted lines in Fig. 3, the counterweight 55 115 acting to facilitate this action and to retain the door 70 in a closed position and the carriage 40 in an inoperative position.

For co-operating with a sound record 51 upon the turntable 50 to reproduce sounds, 120 there is provided a sound box or sound reproducer 80 which carries a stylus 81 which is arranged to engage the sound record 51. The sound box 80 is preferably connected in a well-known manner to one end of a U-shaped tube 82, the other end of which is pivotally connected to the smaller end of a 125 longitudinally tapering hollow tone-arm 83 to swing with respect thereto about a horizontal axis from an operative position in 130

engagement with a record 51 to an inverted inoperative position where it will rest upon a bracket 84 carried by the tone arm.

The tone-arm 83 extends from the U-shaped tube 82 rearwardly in a straight line substantially parallel with the plane of the record support 50 and then curves longitudinally upwardly through an arc of about 90 degrees and terminates in an open substantially cylindrical end 85. The tone-arm 83 is arranged to swing about a fixed axis which is supported by a fixed bracket 87 which is rigidly secured to the smaller end of a longitudinally tapering hollow rigid sound conducting bracket 90 which flares upwardly in the upper compartment 22, the longitudinal axis of the pivot 86 being substantially coincident with the axis of oscillation of the tone-arm, and with the longitudinal axis of the larger end of the tone arm. The lower end of the hollow bracket 90 and the depending bracket 87 project freely through an aperture 91 provided therefor in the front part of the horizontal portion of the partition 20, and at a point such that the axis of oscillation of the tone-arm 83 lies in an approximately vertical plane perpendicular to the back wall 4 of the cabinet and intersecting the central portion of the active path of the stylus 81 across the record 51.

The hollow bracket 90 is rigidly secured to the back wall 4 of the cabinet, the bracket being preferably provided with a flat base 95 integral therewith which is clamped rigidly against the inner surface of the back wall 4 by bolts 96 extending through the back wall and threaded into the base 95. The larger end of the hollow bracket 90 terminates in a transversely oblong rectangular longitudinally flaring socket 97, which is preferably arranged so that its longitudinal axis is horizontal and coincides with the central portion of the sound outlet.

Arranged coaxially with the socket 97 and flaring forwardly therefrom is a hollow sound amplifying body 99 which is entirely supported at its smaller end by the rigid hollow bracket 90, the smaller end of the sound amplifying body 99 fitting snugly in and being rigidly secured to the socket 97. This hollow sound amplifying body 99 is preferably oblong and rectangular throughout its length in transverse section and comprises two wooden forwardly diverging side walls 100 arranged in vertical planes and connected by a plurality of forwardly diverging flat sounding boards 101. This hollow sound amplifying body projects freely from the hollow rigid bracket 90 and terminates at its larger end in close proximity to but spaced from the inner surface of the doors 30 and 31 when the doors are closed.

From the foregoing it is evident that the construction of this improved machine is

such that the record support 50 may be moved automatically from an inoperative position into an operative position simply by opening the door 70 which may be accomplished with very slight effort, and that when the record support is in its operative position, it is conveniently accessible and is so inclined as to facilitate the changing of records, and the door 70 is in such a position that the major portion of its area is serviceable as a convenient shelf or stationary support for holding records or other talking machine accessories during the operation of the machine. By having the forward portion of the partition 20 inclined upwardly and forwardly free access to the record support is provided, and the inclined portion of the partition may be adapted to act as a sound deflector to reflect outwardly any sound waves which may be directed against its under surface as a result of the external action of the sound box 80. The inclined portion of the partition 20 may also coöperate with the inclined carriage and sound record to act as a forwardly flaring sound amplifier for the sound waves produced externally by the sound box. When the machine is not in operation the door 70 may be closed and the machine will occupy only a comparatively small amount of space.

It will be seen that my invention provides an inclosed talking machine in which the tone arm is pivotally mounted to swing across the record as the sound box is propelled, through the stylus, by the record groove, and that the record support 50 supported on the movable carriage 40 in the cabinet, is in an inclined inoperative non-playing position when the closure or door 70 is closed as shown, in dotted lines in Fig. 3, and that when the closure or door 70 is opened, the record support is moved by the closure forwardly to the front of the cabinet and away from its original position within the cabinet and away from the pivotal axis of the tone arm, outwardly from the interior of the main or body portion of the cabinet, transversely to the path of the movement of the stylus and sound box across the record during the reproduction of sound, to an operative playing position, in which the record support preferably projects or extends outwardly somewhat from the main or body portion of the cabinet or casing. In this latter position, the record support 51 is at, near or adjacent the opening in the cabinet, where it is accessible for changing records, changing needles and for regulating the speed of the motor, and in said latter position the sound box is free to traverse the record for the purpose of reproducing sound therefrom.

Although only one embodiment of my invention has been illustrated in the accompanying drawings described in the

above specification, it is to be understood that the invention is not to be construed as limited strictly thereto. Many changes in construction and arrangement are fully contemplated by me and are intended to be included herein, so long as such structures are defined by and are embraced within the plain intent and meaning of the terms of the appended claims.

10 Having thus fully described this invention, I claim and desire to protect by Letters Patent of the United States:

1. In a talking machine, the combination with a cabinet, sound reproducing means arranged therein, of a rotary record support movable independently of said cabinet from an inoperative non-playing position within said cabinet to an operative playing position extending outwardly from said cabinet.

15 2. In a talking machine, the combination with a cabinet and sound reproducing means arranged therein, of a rotary record support movable with respect to said sound reproducing means from an inoperative non-playing position within said cabinet, to an operative playing position away from said position within said cabinet.

20 3. In a talking machine, the combination with a cabinet and sound reproducing means therein, of a rotary record support movable in said cabinet relatively to said reproducing means in a path inclined with respect to said cabinet from an inoperative non-playing position to an operative playing position.

25 4. In a talking machine, the combination of a cabinet having an opening therein, sound reproducing means in said cabinet, a rotary record support within said cabinet and a closure arranged to open and close said opening in said cabinet and to move said record support with respect to said cabinet to an operative playing position at said opening and to an inoperative non-playing position away from said opening.

30 5. In a talking machine, the combination of a cabinet having an opening therein, sound reproducing means in said cabinet, a rotary record support, and a closure arranged to open and close said opening and to move said record support with respect to said cabinet to an operative playing position by the opening of said closure and to an inoperative non-playing position by the closing of said closure.

35 6. In a talking machine, the combination with a cabinet provided with an opening, and a movable closure for said opening, of sound reproducing means within said cabinet, a rotary record support within said cabinet and arranged to be moved by said closure from an inoperative non-playing position inside of said cabinet to an operative playing position at said opening and

sound amplifying means arranged within said cabinet above said record support.

7. In a talking machine, the combination with a cabinet, of an inclined record support arranged within said cabinet and movable from an inoperative non-playing position within said cabinet to an operative playing position outwardly from the interior or said cabinet, stationary sound amplifying means arranged within said cabinet and secured thereto, and sound reproducing means carried by said amplifying means and arranged to coöperate with a record on said support when said record support is in said operative position.

75 8. In a talking machine, the combination of a cabinet, a rotary record support within said cabinet, sound amplifying means in said cabinet above said record support, sound reproducing means, and sound deflecting means extending in said cabinet between said sound amplifying means and said record support in a direction diverging with respect to said record support.

80 9. In a talking machine, the combination of a cabinet, and inclined rotary record support within said cabinet, sound amplifying means within said cabinet above said record support, sound reproducing means, and sound deflecting means extending in said cabinet between said sound amplifying means and said record support in a direction diverging with respect to the plane of said record support.

85 10. In a talking machine, the combination of a cabinet, an inclined rotary record support pivoted on an axis to swing over said support during the reproduction of sound, and a sound box mounted on said tone arm, said record support being mounted to move away from the pivotal axis of said tone arm into an operative relation with respect to said sound box and to move toward said pivotal axis into inoperative relation with respect to said sound box.

90 11. In a talking machine, the combination with a cabinet, of sound reproducing means arranged therein, and a rotary record support movable from an inoperative position within said cabinet to an operative position outwardly from the interior of said cabinet, and means to counterbalance the weight of said record support to facilitate its movement into and outwardly from the interior of said cabinet.

95 12. In a talking machine, the combination with a cabinet, of a movable sound reproducer mounted therein and a rotatable sound record support coöperating therewith, said support being movable with respect to said reproducer in a path transverse to the direction of the relative movement between said reproducer and said record support in reproducing sound from a record, from an inoperative non-playing position within

said cabinet to an operative playing position extending outwardly from said cabinet and vice versa.

13. In a talking machine, the combination 5 with a cabinet, of a closure mounted to oscillate about a fixed axis, a rotary record support arranged to move with respect to said cabinet in an inclined path from an inoperative to an operative playing position, 10 and means connecting said closure and said record support whereby said closure moves said record support through said inclined path upon the oscillation of said closure.

14. In a talking machine, the combination 15 of a cabinet provided with an opening, of a closure for said opening, a rotary record support arranged to move with respect to said cabinet in an inclined path from an inoperative to an operative playing position, 20 and means connecting said closure and said record support whereby said closure moves said record support through said inclined path upon the opening and closing of said

closure, and means to counterbalance the weight of said record support. 25

15. In a talking machine, the combination with a cabinet provided with an opening and a movable closure therefor, of a tone arm having one end pivoted within said cabinet to swing in an inclined plane, a 30 rotary record support and means operatively connecting said closure and record support to move said record support in an inclined path substantially parallel to the plane in which said tone arm swings, from an inoperative position to a playing position, and from an operative playing position to an inoperative position upon the opening and closing respectively of said closure. 35

In witness whereof I have hereunto set 40 my hand this 18th day of September, 1914.

ELDRIDGE R. JOHNSON.
